DRINKING FOUNTAIN

Filed Sept. 24, 1923

2 Sheets-Sheet 2

UNITED STATES PATENT OFFICE.

WILLIAM ROBERTS, OF SPRINGFIELD, OHIO.

DRINKING FOUNTAIN.

Application filed September 24, 1923. Serial No. 664,581.

To all whom it may concern:

Be it known that I, WILLIAM ROBERTS, a citizen of the United States, and a resident of Springfield, in the county of Clark and State of Ohio, have invented certain new and useful Improvements in Drinking Fountains, of which the following is a specification.

This invention relates to an improvement in drinking fountains especially designed for use in schools, public parks and other public places.

The object of the invention is to provide a drinking fountain of this character which is adapted to serve a large number of persons at the same time without the least crowding and which is also sanitary and indestructible and attractive and ornamental in appearance.

Another object is to provide a drinking fountain having the foregoing advantages and capacities and wherein the bubble cups and pipes for supplying the water thereto are completely and quickly drained when the fountain is not in use thereby precluding the possibility of water freezing in parts of the fountain and damaging or injuring the same.

A still further object is to provide a fountain of this character which is comparatively simple in construction and adapted to be manufactured at a comparatively slight cost from materials and by means of facilities ordinarily available and wherein the parts are readily and easily accessible for purposes of cleaning, adjustment, replacement and repair.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a perspective view, illustrating the preferred embodiment of the invention;

Figure 2 is a view thereof in diametrical vertical section;

Figure 3 is a detail view, partly in elevation and partly in section, showing the piping employed for supplying the bubble cups with water;

Figure 4 is a perspective view illustrating the construction of the underside of the bowl;

Figure 5 is a fragmentary perspective view, illustrating the stand pipe and certain of its associated parts; and

Figure 6 is a detail view in vertical section, showing the construction and mounting of the bubble cup.

Referring to the drawings wherein for the sake of illustration is shown the preferred embodiment of the invention, the numeral 10 designates generally a pedestal which is made up of a base block 11 supported on a concrete or other suitable foundation, a tapering block or pillar 12 arranged above and supported upon the base block and a cap block 13 surmounting the tapering block 12. The blocks 11, 12 and 13 are provided with centrally disposed and vertically aligned openings through which a drain pipe 14 extends. The drain pipe 14 is of less diameter than that of the openings through which it extends and the space between the outer wall of the drain pipe and the walls of the openings is slushed with a rich concrete mixture whereby the drain pipe is held in place and a very solid union is had between the blocks making up the pedestal. As shown in Figure 2 the contacting faces of the blocks of the pedestal are inclined and this also tends to hold the blocks in position and against displacement and it is to be understood that the blocks may be bonded together by concrete or otherwise secured together if found desirable. The cap block 13 is centrally recessed, as at 15, and in this recess a drip plate 16 is fitted and secured, the drip plate having a depending nipple 17 fitted in the upper end of the drain pipe 14.

A bowl designated generally at 20, is supported on the cap block 13 and includes a bottom 21 and a heavy rim 22. It is to be understood that the pedestal and bowl is preferably constructed of concrete which is suitably reinforced and preferably granite or marble chips are used in the composition of the bowl and the pedestal so as to permit of either a bush-hammered or polished finish and thereby enhance the attractive appearance and ornamental qualities of the fountain. The upper surface of the bottom 21 of the bowl slopes toward the center thereof as clearly shown in Figure 2 and at the

center an opening 23 is provided, the opening overlying the drip plate 16 and being lined by a bushing 24.

A plurality of bubble cups, designated generally at 25, are disposed within the bowl 20 and preferably are arranged in circular series around and adjacent to the rim 22. In the embodiment of the invention illustrated but ten bubble cups are provided but, obviously however, they may be provided in any desired number. The bubble cups are of identical construction and may be of any conventional form or design and preferably each includes a vertical tube or pipe 26 extending up through the bushing 27 embedded in the concrete making up the base or bottom of the bowl. Around each bushing 27 the upper side of the base 21 of the bowl is provided with a swell or boss 28 so as to provide a mound or raised portion on which each bubble cup is mounted. A nut 28^a is threaded on this pipe or tube 26 and has a flaring collar 29 integral with its lower end which is adapted to tightly engage the boss 28. If desired suitable packing may be introduced between the collar 29 and the boss so as to seal the space around the pipe 26 and prevent the waste water from flowing through the space between the bushing 27 and the pipe 26. At its upper end the pipe 26 carries a jet 30 and a cup 31 having two or more discharge openings 32 arranged to permit the overflow or discharge from the jet to pass immediately and directly into the bowl 20.

The bubble cups 25 are supplied with water by means of a feed pipe, designated generally at 35 and made up of a number of sections 36 coupled by a union 37 and having on each side of the union an arrangement of L's designated generally at 38. The feed pipe is coupled, as at 39, with one of a number of distributing pipes 40 which are arranged to extend radially of the bowl and are accommodated in openings or slots 41^a provided therefor in the under side of the bowl. The pipes 40 are connected at their outer ends with branch pipes 41 coupled to the lower ends of the tubes or vertical pipes 26 by means of T's 42 and accommodated in openings or slots 41^b. At their inner ends the pipes 40 are connected to a short cylinder 43 the lower end of which is closed, as at 44, and is provided with an adjustable and threaded plug 45 drilled lengthwise and arranged so that its upper end is immediately below the lower side of the ends of the pipes 40 connected to the cylinder 43. The upper end of the cylinder 43 is open and has threaded connection with a stand pipe 46 which is disposed vertically of the bowl since the cylinder 43 is disposed centrally of the drain opening 23. A cap 48 is threaded on the upper end of the stand pipe 46 and is provided with a number of perfora-

tions 49. This cap 48 also serves to hold in place an ornamental dome 50 constructed of metal or concrete and arranged to surround the stand pipe and rest at its lower edge or end on the bottom of the bowl around the drain opening thereof, the lower edge of the dome being provided with a series of openings 51 to admit of free flow of the water past the dome on its way to the drain opening. As indicated in detail in Figure 5 the bushing 24 is provided with a number of openings 24^a accommodating the pipes 40. The T's 42 provided at the lower ends of the vertical tubes 26 of the bubble cups are provided with a sediment collecting chamber 80 53 and having a removable plug 54 therein to admit of cleaning. It is to be understood of course that the feed pipe is provided with a suitable valve not shown and preferably the valve is located at a point where it is 85 not liable to be tampered with by children or unauthorized persons.

With this arrangement when the fountain is started the water flows through the feed pipe into the pipe 40 with which it is connected. From the pipe 40 it flows into a short cylinder 43 and up through the stand pipe. For a short time after the fountain is started the water will issue through the perforations 49 in the cap of the stand pipe 95 but in a few moments the water will be evenly distributed from the cylinder 43 to all of the bubble cups and will issue in uniform jets therefrom. In practice it has been found that with the size of fountain 100 illustrated very satisfactory results are obtained by utilizing a feed pipe of $\frac{3}{4}$ inch diameter, a section 40^a of a $\frac{1}{2}$ inch pipe and all of the other pipes of $\frac{3}{8}$ inch diameter. Of course the invention is not to be 105 restricted to these dimensions but it is believed to be instructive to those skilled in the art to refer to the same here. The water which issues from the jets of the bubble cups and which is not consumed falls through the opening 32 onto the upper side of the bottom of the bowl from whence it quickly drains through the opening 23 onto the drip plate 16 and thence into the drain pipe 14. When the fountain is stopped or 110 out of use it is quickly drained so as to preclude freezing in any of the pipes or bubble cups and this is rendered possible by virtue of the drilled plug 45, and its relation and arrangement in the chamber or short cylinder 43 to the pipes 40 for obviously when the supply of water is cut off, the water contained in the bubble cups and in the pipes 40 and 41 as well as in the stand pipe 46 will be quickly drained through the 115 lengthwise opening of the plug 45. It is to be understood that the leakage through this small opening or bore of the plug 45 when the fountain is in use is very slight and does not affect the operation of the 120

fountain. Moreover the short cylinder 43 provides a trap or collecting basin for sediment, sand or the like liable to be contained in the water, and precludes the possibility 5 of the same stopping up the fountain. Additional traps are provided by means of the chambers 53 in the T's provided for connecting each of the vertical tubes of each bubble cup to its water supply pipe. The 10 weight of the bowl and the connection of the feed pipe has been found to be sufficient to hold the bowl in place but obviously other means may be employed for this purpose if considered desirable.

15 The fountain is sanitary, practical and affords drinking facilities for a relatively large number of people at the same time.

I claim:

1. A drinking fountain including a 20 pedestal having a central vertical opening, a drain pipe in said opening, a bowl supported on said pedestal and including a bottom and a rim, the bottom having a central drain opening communicating with the 25 drain pipe and having its upper surface sloping to said central drain opening, a plurality of bubble cups arranged in the bowl around the rim and discharging into the bowl, the underside of the bottom of the 30 bowl being provided with a plurality of slots, and pipes for supplying water to said bubble cups arranged in said slots.

2. A drinking fountain including a 35 pedestal having a central vertical opening, a drain pipe in said opening, a bowl supported on said pedestal and including a bottom and a rim, the bottom having a central drain opening communicating with the

drain pipe and having its upper surface sloping to said central drain opening, a 40 plurality of bubble cups arranged in the bowl around the rim and discharging into the bowl, the underside of the bottom of the bowl being provided with a plurality of slots, pipes for supplying water to said bubble cups arranged in said slots, a central stand pipe communicating with all of said pipes and extending upwardly of said central drain opening and disposed centrally 45 of said bowl, and a perforated cap for the upper end of the stand pipe.

3. A drinking fountain including a pedestal having a central vertical opening, a drain pipe in said opening, a bowl supported on said pedestal and including a 50 bottom and a rim, the bottom having a central drain opening communicating with the drain pipe and having its upper surface sloping to said central drain opening, a 55 plurality of bubble cups arranged in the bowl around the rim and discharging into the bowl, the underside of the bottom of the bowl being provided with a plurality of slots, pipes for supplying water to said bubble cups arranged in said slots, a central stand pipe communicating with all of said 60 pipes and extending upwardly of said central drain opening and disposed centrally of said bowl, a perforated cap for the upper end of the stand pipe, and a dome 65 surrounding the stand pipe and held in position by said cap, said dome having openings around its lower end to admit of free flow of water to said drain opening.

WILLIAM ROBERTS.
